[73] Assignee: Honeywell Consumer Products, Inc., Southborough, Mass.

[57] CLAIM

The ornamental design for a humidifier with outlet grill and medicine cup, as shown.

DESCRIPTION

FIG. 1 shows a front, top and left side perspective view of a humidifier with outlet grill and medicine cup incorporating our new design;

FIG. 2 shows a front elevational view of the humidifier shown in FIG. 1, the rear elevational view being a mirror image of the front elevational view;

FIG. 3 shows a left side elevational view of the humidifier shown in FIG. 1;

FIG. 4 shows a right side elevational view of the humidifier shown in FIG. 1;

FIG. 5 shows a top plan view of the humidifier shown in FIG. 1; and,

FIG. 6 shows a bottom plan view of the humidifier shown in FIG. 1.
